UNITED STATES PATENT OFFICE.

PAUL MONTAMAT, OF MARSEILLE, FRANCE.

CASE FOR CONTAINING AIR TUBES OF PNEUMATIC TIRES.

Application filed November 21, 1921. Serial No. 516,754.

To all whom it may concern:

Be it known that I, PAUL MONTAMAT, a citizen of the French Republic, residing at Marseille, Bouches du Rhone, France, 5 433 Rue Paradis, have invented new and useful Improvements in Cases for Containing Air Tubes of Pneumatic Tires, which are fully set forth in the following specification.

10 This invention has for its object a case for containing air-tubes of pneumatic tires for motor-cars, motorcycles, safety-bicycles, and the like.

Mostly the air-tubes are stored into bags 15 made of rubbered canvas which afford only a weak protection against the shocks or the friction received from tools or other various objects, with which they are liable to come in contact into the chests of a motor-20 car. Very scarce are, indeed, the careful drivers who keep available into their car a special place in which the air-tubes are secure from contact with any object liable to injure them. The small room available 25 into the chests of a motor-car for tourism contributes largely to the practice (noxious for the air-tubes) consisting to locate them wherever it is possible without minding for the neighbourhood of objects liable to injure them. Thus it happens frequently 30 that, at the moment when, on a road and far from any help, an air-tube is wanted, which is deemed to be thoroughly reliable upon because it has been placed a few times 35 before into the chest, said air-tube is found to be pierced or worn out by the friction against the corner of a can or the teeth of a lifting-jack with which it was in contact.

It is for the purpose of avoiding these 40 draw-backs, which are still enhanced by the actual rise in price of the air-tubes, that the case constituting the object of the present invention has been designed; its form and its closing device may vary, but 45 its construction is such that it possesses always the following characteristic features, namely:

1st.—To be able to resist to the external 50 shocks and frictions, as well as to the physical and chemical agents, such as light, greases and the like, capable of acting upon the india-rubber.

2nd.—To leave in the interior of the case 55 no corner, asperity or any part whatever liable to injure the air-tube;

3rd.—To avoid any friction, due to the

jars and vibration of the car, of the air-tube against its case.

It may be ascertained, indeed, that an air-tube carefully enclosed into a wooden 60 box and, consequently, secure from any contact with the external objects, may be re-found having the edges of its folds worn out, if it has room enough in said box for moving itself therein under the action of 65 the jars.

The kind of case being the object of the present invention realizes these various conditions.

Said case will now be described with reference 70 to the accompanying drawings in which:

Figures 1, 2, 3 illustrate a first embodiment of the invention.

Figure 1 is an external view of the case 75 closed and containing an air-tube.

Figure 2 shows said case opened.

Figure 3 is a plane view showing the interior of one half of the case.

This case, which may be made of sheet-80 iron, wood, strong cardboard, or any other suitable material, will have, as a rule, a cylindrical shape, as in the example shown, but it may also receive another shape, provided that the air-tube which is stored 85 therein may be easily accommodated in its interior.

The cylindrical case illustrated in the drawings is formed of two parts 1, 2 meeting each other in a diametral plane and 90 connected together by a hinge 3.

When the case is closed, its two halves 1 and 2 may be assembled by means of a rod 4 which is engaged into the sockets 1', 2' formed on the generatrix connecting said 95 two parts 1 and 2.

The cylindrical wall of the case comprises, at 5, a cavity for enabling the passage of the valve 6' of the air-tube 6 contained into the case, as shown in Figure 1.

The case is provided internally with a coating of felt 7 intended to avoid the contact of the air-tube with the wall of the case and to prevent thus any wear of the air-tube caused by the friction.

The case may be provided with a device 100 capable of giving an indication of the actual condition of the air-tube located therein.

Said device consists of a disc 8 applied internally close to one of the bases of the 110 cylindrical case and mounted upon a pivot 9 around which it may be rotated, said

disc bearing several indications, such as: Fresh—Repaired—Burst—Torn out, which indicate the condition of the air-tube, and, when an air-tube is placed into the case, this disc is brought to the proper position for exposing in the window the corresponding inscription.

Figure 4 shows an external view of another constructional form of the case for air-tubes, which consists of a cylindrical body 10 upon which are adapted two covers 11 and 12. These covers are assembled with the body 10 by means of two rods 13 secured, at one end, to the cover 11 and engaging, at their other threaded end, into holes provided in the lugs 12' of the cover 12.

Said rods 13 receive, upon their threaded end, nuts 14.

20 The opening of the case is effected by unscrewing the nuts 14 and removing the cover 12. The cylindrical body 10 comprises an aperture 5 for allowing the passage of the valve of the air-tube. In this form of the 25 device the above described indicating means 8 and 9, is of course also employed in the same manner as described above.

It will be seen that in either of these structural forms, the valve of the air-tube 30 remains exterior to the case. This feature is important, as it is thus possible, when the air-tube is enclosed into the case, to inflate slightly said air-tube by means of a pump, so as to compel it to adhere to the case, thus 35 avoiding any tossing of the air-tube and the wear resulting therefrom.

The invention is hereinbefore described with its essential characteristic features and may, of course, be carried out with any 40 changes or modifications not altering said features.

Thus, as before stated, the case may be made of any suitable material, such as metal, wood, cardboard, and the like; it may receive a cylindrical, elliptical, rectangular, or any other shape, with rounded, square, rectangular, or otherwise shaped ends; it may be provided, or not, with the device indicating the condition of the air-tube contained therein, said device consisting, for instance, of a rotary disc or a movable plate made in any suitable manner; the mode of construction of the case for enabling the opening thereof may also be realized in various manners.

Claims—

1. A container for air tubes, comprising, a two part casing, one part of the casing being apertured to accommodate an air tube valve and an indicator in combination with the casing for indicating the condition of an air tube contained in the casing.

2. A container according to claim 1, said indicator comprising an apertured portion in the casing, and a member, said aperture being wholly within the said one part connected to the casing, and carrying legends registrable with the aperture.

3. A container for air tubes, comprising, a cylindrical casing, the curved cylindrical wall of the casing being apertured for receiving an air tube valve, said valve being wholly disconnected from the casing and free to adjust itself, whereby to permit reception of an air tube in the casing, without sharp turns or bends of the air tube.

In testimony whereof I have signed this specification.

PAUL MONTAMAT.
